UNITED STATES PATENT OFFICE.

LEO CARTIER, OF SAN FRANCISCO, CALIFORNIA.

DESIGN FOR A SMOKER'S TRAY.

52,560.

Specification for Design.

Patented Oct. 15, 1918.

Application filed May 6, 1918. Serial No. 232,952. Term of patent 7 years.

To all whom it may concern:

Be it known that I, LEO CARTIER, a citizen of Canada, residing at San Francisco, in the county of San Francisco and State of California, have invented a new, original, and ornamental Design for a Smoker's Tray, of which the following is a specification, reference being had to the accompanying drawing, forming part thereof, and wherein is illustrated a view in perspective of a smoker's tray, showing my new design.

I claim:

The ornamental design for a smoker's tray, as shown.

LEO CARTIER.

Witnesses:

O. W. YEARGAIN,
M. V. COLLINS.
